DIAL FEED MECHANISM

Leonard F. Peyser, Mount Vernon, and Richard C. Hansen, Eastchester, N. Y., assignors to Peyser-Hansen Machine Co., Inc., Mount Vernon, N. Y., a corporation of New York

Application March 21, 1939, Serial No. 263,148

4 Claims. (Cl. 113—115)

This invention relates to machines of the character that employ an intermittently rotatable dial feed to move a body, such as a container, into and out of position.

The invention is an improvement on the construction shown in Letters Patent No. 1,987,209 of January 8, 1935. In the construction shown in that patent a cam and a clutch were employed to effect the turning movement of the dial feed shaft whereby it was possible to utilize a considerable portion of the revolution of the cam to produce the turning movement of said clutch and shaft. Difficulties were, however, encountered in obtaining accurate indexing of said dial feed shaft. It is the main object and feature of this invention to obtain more accurate indexing of the dial feed shaft by omitting the clutch, while retaining the advantages of utilizing a large portion of the working cycle of the apparatus in which to effect a turning movement of the dial feed shaft.

In the accompanying drawings the invention is disclosed in a concrete and preferred form in which:

Fig. 1 is a side view, partly in elevation and partly in section, of a seaming machine embodying the invention;

Fig. 2 is a horizontal sectional view substantially on the plane of line 2—2 of Fig. 1;

Fig. 3 is a horizontal sectional view substantially on the plane of line 3—3 of Fig. 1;

Fig. 4 is a vertical sectional view substantially on the plane of line 4—4 of Fig. 2;

Fig. 5 is a vertical sectional view substantially on the plane of line 5—5 of Fig. 1;

Fig. 6 is a horizontal sectional view substantially on the plane of line 6—6 of Fig. 1; and

Fig. 7 is a diagrammatic view similar to Fig. 2 showing the movement of certain parts.

1 indicates a reciprocating pedestal to receive a body, such as container 2, so that a cover 3 may be seamed to said body by seaming rollers 4 in a well understood manner. 5 indicates a dial feed, the wings of which move the containers

45 from a suitable conveyor (not shown) to the pedestal and, after the seaming operation has been completed, off the pedestal. 6 is a dial feed shaft which is turned intermittently a fraction of a revolution to effect the discharge and

50 feed of the containers. 7 is a cam shaft, making here one revolution to each reciprocation of the pedestal, and this shaft carries a cam 8 that actuates cam lever 9, pivoted at 10, and thereby effects up and down movement of the pedestal

55 by the forked end of said lever engaging yoke 11

having a spring 12 that engages collar 13 pinned at 14 to the pedestal.

The means for driving the dial feed shaft are as follows: 15 indicates a driving ratchet keyed to shaft 6 and 16 is a driving pawl to engage the driving ratchet. Said driving pawl is actuated from transmission member 17, here in the form of a gear, mounted loosely on dial feed shaft 6. Driving pawl 16 is not carried directly on transmission member 17, but is pivoted at 18 on a ring 19 mounted loosely on an upper extension 20 of gear 17. 21 indicates a block slidable in groove 22 of extension 20 and ring 19, and this block is carried by a bolt 23 mounted in ring 19. 24 is a spring that is interposed between block 21 and the end of groove 22. 25 is a spring that urges driving pawl 16 into engagement with driving ratchet 15. 26 is a stop pawl pivotally mounted at 27 on an extension of the framework to engage driving ratchet 15 and thereby prevent backward rotation. It will be seen from the foregoing that oscillation of gear 17 will, through the yielding connection afforded by block 21 and spring 24, oscillate ring 19 and thereby cause driving pawl 16 to intermittently turn driving ratchet 15, and thereby dial feed shaft 6, a fraction of a revolution.

28 indicates an indexing ratchet mounted fast on dial feed shaft 6 so as to move in unison therewith and with driving ratchet 15, the teeth of said indexing ratchet in the present instance facing in a direction opposite to that of the teeth of the driving ratchet. 29 is an indexing pawl that is moved out of and into the path of the indexing ratchet so as to permit driving ratchet 15 to advance shaft 6 and so as to positively limit the advancing movement thereof. Indexing pawl 29 is carried by an arm 30 pivoted at 31, said arm 30 being oscillated by cam 32 on shaft 7 that engages cam roll 33 on arm 30. 34 is a spring that urges roll 33 against cam 32.

The means for oscillating gear 17 are in the present instance as follows: 35 is a gear sector that meshes with 17 and is carried by an arm 36 pivoted at 31 and receiving its motion from cam 37 on shaft 7. 38 is a cam roll carried by arm 36 and engaging cam 37.

It will now be understood that rotation of cam shaft 7 causes, during each of its revolutions, pedestal 1 to be lifted and lowered, and dial feed shaft 6 to be advanced a step and to be properly indexed and stopped. The throw of cam 37 and the amplitude of the movement of gear sector 35 are such that gear 17 has a greater stroke than that required by driving pawl 16 to advance

driving ratchet 15 the proper distance. This excess movement is indicated by the dotted line position of the parts in Fig. 7, and the object of this overstroke is to render certain that the dial feed 5 shaft will always be advanced sufficiently. Indexing pawl 29, by its movement into the path of indexing ratchet 28, will prevent the excess movement being transmitted to driving pawl 16 because when said indexing pawl stops the indexing 10 ratchet it will also stop the driving ratchet and ring 19 and the excess movement will be taken up by the yielding connection consisting of block 21 and spring 24.

We claim:

- 15 1. In a dial feed mechanism in which a dial feed shaft is intermittently turned a fraction of a revolution in one direction only: a driving ratchet mounted fast on the shaft, an indexing ratchet, also mounted fast on the shaft; a driving 20 pawl to engage the driving ratchet; an oscillatory transmission member, to actuate the driving ratchet, mounted loosely on the shaft; an indexing pawl, to engage the indexing ratchet, mounted independently of the shaft and transmission 25 member; and means to move the indexing pawl out of and into the path of the indexing ratchet to thereby allow the driving pawl to move the driving ratchet and to limit the movement of the driving ratchet.
- 30 2. In a dial feed mechanism in which a dial feed shaft is intermittently turned a fraction of a revolution in one direction only: a driving ratchet mounted fast on the shaft; an indexing ratchet, also mounted fast on the shaft; a driving 35 pawl to engage the driving ratchet; an oscillatory transmission member, to actuate the driving ratchet and having a greater stroke than that required by the driving pawl, mounted loosely on the shaft; a yielding connection between the oscillatory member and driving pawl; an indexing pawl, to engage the indexing ratchet, mounted independently of the shaft and transmission member; and means to move the indexing pawl 40 out of and into the path of the indexing ratchet to thereby allow the driving pawl to move the driving ratchet and to limit the movement of the driving ratchet and driving pawl.

out of and into the path of the indexing ratchet to thereby allow the driving pawl to move the driving ratchet and to limit the movement of the driving ratchet and driving pawl.

3. In a dial feed mechanism in which a dial feed shaft is intermittently turned a fraction of a revolution in one direction only: a driving ratchet mounted fast on the shaft; an indexing ratchet, also mounted fast on the shaft, the teeth of which face in the direction opposite to that of the teeth of the driving ratchet; a driving pawl to engage the driving ratchet; an oscillatory transmission member, to actuate the driving ratchet, mounted loosely on the shaft; an indexing pawl, to engage the indexing ratchet, mounted independently of the shaft and transmission member; and means to move the indexing pawl out of and into the path of the indexing ratchet to thereby allow the driving pawl to move the driving ratchet and to limit the movement of the driving ratchet.

4. In a dial feed mechanism in which a dial feed shaft is intermittently turned a fraction of a revolution in one direction only: a driving ratchet mounted fast on the shaft; an indexing ratchet, also mounted fast on the shaft, the teeth of which face in the direction opposite to that of the teeth of the driving ratchet; a driving pawl to engage the driving ratchet; an oscillatory transmission member, to actuate the driving ratchet and having a greater stroke than that required by the driving pawl, mounted loosely on the shaft; a yielding connection between the oscillatory member and driving pawl; an indexing pawl, to engage the indexing ratchet, mounted independently of the shaft and transmission member; and means to move the indexing pawl out of and into the path of the indexing ratchet to thereby allow the driving pawl to move the driving ratchet and to limit the movement of the driving ratchet and driving pawl.
